DRY CLOSETS

George O. Harm, Shaker Heights, Ohio

Application December 28, 1955, Serial No. 555,892

12 Claims. (Cl. 110—9)

This invention relates broadly to mechanism for the combustion of fecal matter and urine, and more specifically to improvements in the combination of a closet and incinerator designed for use in a home, factory, summer cottage, camps, mobile units and like environs.

One of the objects of the invention resides in the provision of a closet embodying a continuous strip of water resistant combustible film such as sized paper, and mechanism for progressively forming the strip of film into a trough for the reception of fecal matter and urine, and then to fold and flatten it and the contained fecal matter into a thin flat product susceptible of ready combustion in an incinerator associated therewith.

Another object of the invention is to provide a closet having a support therein for the trough of film before it enters the flattening stage, and to further provide rollers and associated drive means in the closet adjacent the end of the trough support to move the strip of film through the closet, fold and flatten it around the fecal matter carried thereby for entry into an incinerator disposed in contiguous relation with the closet.

Another object of the invention is to provide an incinerator designed to produce a temperature which will effect the complete combustion of the film and fecal matter and urine with dispatch and without emitting offensive odors.

Another object of the invention is to provide a unit which is relatively small in size, light of weight, and economic of manufacture, which will meet the need of home owners in areas not provided with a sanitation sewer.

Other objects and advantages more or less ancillary to the foregoing, and the manner in which all the various objects are realized, will appear in the following description, which considered in connection with the accompanying drawings, sets forth the preferred embodiment of the invention.

Referring to the drawings:

Fig. 1 is a plan view of the improved closet and incinerator;

Fig. 2 is a side elevational view thereof;

Fig. 3 is a vertical sectional view through the closet, the section being taken on a plane indicated by the line 3—3 in Fig. 4;

Fig. 4 is a transverse sectional view of the closet, the section being taken on a plane indicated by the line 4—4 in Fig. 3;

Fig. 5 is an enlarged vertical section taken on a plane indicated by the line 5—5 in Fig. 3;

Fig. 6 is an enlarged detail view of the roller drive mechanism, the section being taken on a plane indicated by the line 6—6 in Fig. 4;

Fig. 7 is a transverse sectional view through the closet and incinerator, the section being taken on a plane indicated by the line 7—7 in Fig. 8;

Fig. 8 is a sectional view of the incinerator, the section being taken approximately on the line 8—8 of Fig. 7;

2

Fig. 9 is an enlarged sectional view facing the incinerator, the section being taken on the line 9—9 of Fig. 7;

Fig. 10 is a sectional view of a fragmentary portion 5 of the incinerator, the section being taken on the line 10—10 of Fig. 9;

Fig. 11 is a detail view in section, the section being taken on the line 11—11 in Fig. 9;

Fig. 12 is a detail view of a fragmentary portion of the 10 plate valve actuating linkage; and

Fig. 13 is a wiring diagram of the incinerator control mechanism.

Referring first to Figs. 1 and 2, the unit comprises a closet 10 having an incinerator 11 attached thereto and a stack 12 mounted on top of the incinerator to carry off the heat generated therein. The top of the incinerator is formed with an opening 95 for access to the interior thereof. The opening is provided with a cover 96 embodying subtended legs 97 (Figs. 7 and 8) supporting secondary plates 98 in alignment with the inner walls of the incinerator. The closet which may be made of any suitable material, comprises a rectangular body having a depending oval bowl 13, preferably designed to rest on the floor, and an integral square housing 14 protruding from the rearward portion of the body for the reception of the forming rollers, drive gearing, and the adjustment mechanism therefor. As will be seen in Figs. 3 and 4, the interior of the closet is provided with a rectangular frame 15 fulcrumed adjacent the top thereof upon a shaft 16 mounted in bearing blocks 17 affixed to the inner side walls of the housing 14.

The frame is inclined downwardly and rests upon a jack screw 18 engaged with the wall of the bowl 13, the sides of the lower end of the frame are provided with brackets 19 drilled and reamed to support a pair of shafts carrying flanged rollers 20 and 21 spaced to support a roll of paper 22, or a film of a similar character. The shafts are designed for axial adjustment in the brackets, and may be locked in position by set screws mounted in the brackets. The rollers idle on the shafts and are spring pressed against nuts affixed to the ends of the shafts. The central portion of the frame 15 supports a strut 15a, which in turn, supports a downwardly inclined triangular plate 23 having side walls 24 extending upwardly from near the apex of the triangle to the base thereof. The top of the plate 23 is disposed within the forward end of the bowl 13 and is formed with a horizontal rolled edge 25, while the lower ends of the upturned side walls are vertical and terminate in front of the opening between a pair of spaced rollers 26. Adjacent the ends of the rolled edge 25 there are provided shoes 30 bent to deflect the paper 28 within the side walls 24. When the strip of paper or film 28 is brought from the supply roll 22 over the rolled edge 25 of the plate 23, and the edges deflected upward by the shoes 30, thence folded vertically and passed between the spaced rollers 26, a triangular shaped trough of paper or film is formed over and within the plate 23 and the converging side walls 24 for the reception of fecal matter and urine. The circumferential faces of the rollers 26 are cross-knurled to grip and draw the paper, together with the fecal matter carried thereby, between the rollers during the rotative cycle thereof.

The rollers 26, (Figs. 5 and 6) are hollow and counterbored to receive end plates 31 which are bored for running clearance on shafts 32 affixed in and depending from bell cranks 33 and 34 mounted on the shafts 16. The bell crank 33 is drilled and tapped to receive a screw 35 bored for sliding engagement on the shaft 16, and a sleeve 36 is mounted on the shaft in abutting engagement with a boss 37 on the inner face of the frame

15. Lateral movement of the bell crank and the roller supported thereby is attained by adjustment of the screw 35. The bell crank 34 is drilled to receive a bushing 38 mounted for free rotational movement on the shaft 16, and a second sleeve similar to the sleeve 36 is mounted on the shaft 16 in abutting engagement with the bushing 38. The inner arm 39 (Fig. 6) of the bell crank 34 is machined for the rotative support of a shaft 40, the outer end of which is provided with a crank arm 41 (Fig. 4) for actuating the shaft, while the inner end thereof supports a ratchet wheel 42 bushed for rotational movement on the shaft. The ratchet wheel is affixed to a pulley 43, and an arm 44 secured on the shaft 40 adjacent the ratchet wheel, supports a pawl 45 engaged with the teeth of the ratchet wheel. The teeth of the ratchet are formed to rotate the pulley clockwise upon forward and downward rotation of the arm 41. A pin 46 is mounted in the outer end of the arm 44 to delimit the movement of the pawl 45 upon retraction of the arm 41. The outer leg 47 of the bell crank 34 is bored for the reception of a pin 49 having an eccentric pintle 48 therein which supports a sheave 50, and a belt 51 is roved over the pulley and sheave, the central portion of the lower run thereof being impinged between the paper film 28 and the walls of the upper ends of the rollers 26. The pin 49 is locked in position by a set screw 52, but the sheave may be adjusted to align the belt into parallel relation with the ends of the rollers by loosening the screw and adjusting the pin 49. Both the bell cranks 33 and 34 are formed with integral upward and outwardly directed arms 53 having slots in the outer ends thereof to receive lock screws threaded in the ends of bolts 54. The bolts are threaded in bosses 55 in the cross member of the frame 15 and abut washers 56 on the arms 53, thus facilitating rocking adjustment of the bell cranks about their fulcrums on the shaft 16. The cross member of the frame 15 is further provided with a bracket 57 for the support of a sheave wheel 58 engaged with the belt 51 which is adapted to vary the tension thereon upon adjustment of the bracket 57 and holding it in place by means of bolts 55a.

The operative adjustment of the mechanism is attained by rocking the bell crank until the proper position of the rollers' axes in relation to the run of the paper is attained, the locking the arms 53 of the bell cranks against the bolts 54 by adjustment of the screws 54a. Lateral pressure on the belt 51 is attained by the adjustment of the screw 35.

The edges of the folded strip of film are compressively engaged on either side of the belt and the top portions of the rollers. With the rearward translation of the belt, the strip of film is drawn from the supply roll across the plate, and the folded strip with the fecal matter carried thereby will be rolled into a relatively flat thin product suitable for burning with an economy of fuel.

As illustrated in Figs. 1, 2 and 3, the top of the closet 10 is provided with a cover plate 65 conforming to the lineation of the bowl and housing, and formed with depending oval flange 59 superjacent the forward end portion of the inclined plate 23. The top of the remaining portion of the cover plate is formed with an outer depending flange 60 which conforms with the top of the bowl and forms a housing for the pulley 43 and the mechanism associated therewith. The cover is held in place by lugs 61 affixed within the bowl in the corners thereof and protruding upwardly to arrest lateral movement of the flange 60. The cover plate is provided with a toilet seat 62 of conventional form, hinged adjacent the rear end thereof, the opening in the seat being aligned vertically over the trough of film heretofor described.

Referring now to Figs. 1, 2, 7, 9 and 11, the closet 10 is attached to the incinerator 11 through a rectangular sheet metal breeching B, having a valve therein 75

comprising a fixed plate 63 padded with a soft heat resisting material, and a second reciprocative plate 64 designed to close the opening in the incinerator that communicates with the closet. The padding on the plates 63 and 64 is provided with grooves 66 adjacent the lower ends thereof to accommodate the flow of liquids to an evaporating pan 67 forward the burner nozzle 84b in the base of the combustion chamber 69. The padding on the plates 63 and 64 is impregnated with flame inhibiting chemicals of any well known form to extinguish the flame which might work back from the combustion chamber.

The plate 64 is actuated by a bar 70 supported for reciprocative movement in guide straps 71 mounted on an outer side wall of the incinerator. The incinerator is formed with a sheet metal housing that surrounds the incinerator assembly. The bar 70 is secured to the valve plate 64 and is pivotally connected, adjacent its outer end, through a slotted hole, to a lever 73 fulcrumed in the center thereof to the side wall of the housing. The upper end of the lever 73 is provided with an open socket 74 disposed at an angle of approximately fifteen degrees (15°) to the major axis thereof. The socket receives a rod 75 mounted in a collar 76 on the flanged hub 72 which is keyed to the shaft 40, and a delayed movement of the hub 72 is provided by a pin 77 seated in the flanged hub which protrudes into an arcuate slot 78 in the collar, of approximately twelve degrees (12°) in length. The collar is restrained against axial movement by a snap ring 76a seated in a groove in the hub. The collar assembly is normally held in full line position, as illustrated, by a spring 80 anchored to the collar 76, and to the floor. In operation, the crank arm 41 travels from its full line position to the dotted line 81 before the shoulder defined by the slot 78 reaches the pin 77. As this occurs, the rod 75 will rock the lever 73 as it ascends in the angularly disposed socket 74 and open the valve 64. Continued movement of the arm 41 to the dotted line position 82 will effect the rotation of the rollers 26 and the passage of the folded film and the flattened fecal matter contained therein into the combustion chamber. The spring 80 will effect the return movement of the arm 41 to the closed position of the valve plate 64.

The flame generating mechanism of the incinerator is the conventional type comprising a blower 83 and fuel pump 89 both driven by the motor 113. The blower compresses the air within the housing 83a from whence it is discharged through perforations in the cone 84a surrounding the fuel nozzle 84b which is at the end of the fuel line 84. An ignitor 91 ignites the mixture of air and fuel producing a flame which is projected into the combustion chamber 69 and the exhaust conduit 86 by the combined action of air velocity and the combustion of the fuel. A removable evaporating pan 67, having a beveled edge 87 forms the top of the horizontal portion of the conduit 86 and is adapted to receive liquids which drain through the narrow U shaped channel formed when the film is folded between the rollers. The folded strip of film enters the combustion chamber 69 through the port 79 which is a continuation of the breeching B. A grid 88 is placed in the combustion chamber to prevent the folded strip of film from falling over and obstructing the path of the flame into the exhaust conduit 86. In operation, about one-third of the flame sweeps across the top of the pan igniting and consuming the folded strip of film and the thin section of fecal matter which it carries. The smoke, steam and other products of combustion travel downward and are drawn into that portion of the flame which enters the exhaust conduit directly from the burner and are consumed by the high heat of this flame so that odors in the final exhaust gases are eliminated.

The shell 85 of the combustion chamber is surrounded

by a second shell 85a providing an insulating air passageway which receives air from the housing 83a through the opening 92 and discharges it through the opening 92a into the stack 12 which surrounds the exhaust conduit 86. The assembly of parts of the incinerator as described, are enclosed in a housing 11 which number is also used to designate the incinerator as a unit.

From the foregoing, it will be seen that the folded strip of film will support the fecal matter and urine which may be deposited thereon, that the rollers will extrude the folded film and contained fecal matter into a thin, flat product, and that the flame from the burner in the incinerator will effect the ready and complete combustion of the film and fecal matter and urine without emitting offensive odors.

Referring to Fig. 13, the blower 83, fuel pump 89, valve 90 therefore and the lighter or ignition device 91 are automatically controlled through an electric timer 106 actuated by a starting switch actuated by the hand lever 41. As will be seen in Fig. 9, the end of the bar 70 is arranged to abut the stem of the switch 101, which is normally held in its open position by a spring. When the switch is closed, current from the power line 104 will flow through the line 105, the switch 101, the timing motor 106 and to the ground line 107, thus exciting the motor and initiating the rotation of a sweep arm 108 in the timer 106. The sweep arm 108 is formed with a broad land 118 on the free end thereof. As the land 118 leaves the switch 119, it is closed under the influence of a spring therein, current from the line 104 will flow through the line 110, switch 119, and an extension of the line 105 to the timing motor 106, thence to the ground line 107. Such action assures the continued operation of the timer. When the sweep arm reaches the switch 109, the plunger therein will be actuated to close the circuit through the lines 104, 110, 111 and 112 to the motor 113 for the blower 83, fuel pump 89 and ignition device 91 and thence to the ground line 107. When the arm 108 reaches the spring pressed switch 115, current from the line 104 will flow through the line 116, the switch 115, and the continuation of the line 116 to a solenoid 117 for the fuel valve 90. This valve is normally held in its closed position by a spring, but it held open by the solenoid 17 while the current flows through line 116, the solenoid, and the continuation of the line 116 to the ground line 107. The land 118 further maintains the switch 115 in its closed position for a normally sufficient period to sustain the flame. The valve stem rod 114 for the valve switch 120, is formed of an expandable material which is disposed in the path of the flame from the burner. When the valve stem rod is heated and expanded, the switch 120 is closed and the current will flow through the lines 104, 130, switch 122 and line 121, the switch 120 and the lines 121 and 116, thus holding the solenoid 117 for the valve 90 in an open position.

In the event the flame goes out in the incinerator, the rod 114 in the switch 120 will contact and open the circuit to the solenoid valve 117, thus breaking the circuit from the lines 104, 130, switches 122, 120 to the line 121, thus shutting off the fuel. The circuit through the switch 115 has by this time been broken by the movement of the sweep arm 108. When the flame is burning, as in normal operation, with the switch 120 closed, the continued movement of the sweep arm 108 will engage and open a spring pressed switch 122, thus breaking the circuit which has been holding the solenoid 117 open and causing the valve operated thereby to close under the influence of the spring therein. The solenoid 117 cannot be reactivated during the cycle, since the rod 114 contracts when the flame goes out and breaks the circuit in the switch 120. When the arm reaches the switch 123 which is held open by a spring therein, the solenoid 124 in the switch 109 will open the switch and break the cir-

cuit to the motor for the blower 83, fuel pump 89 and ignitor 91. Current from the line 104 will, however, flow through the line 110, the switch 119, the line 105 to the timer motor 106 which continues to run until the sweep arm 108 reaches the switch 119 and breaks the current to the line 105.

The switches 122 and 123, which stops the burning action of the fuel, are mounted on a carriage 131, rotatable from a center common to the sweep arm 108. Movement of the carriage 131 varies the timing cycle of combustion of the fuel.

The evaporating pan 67, which is electrically insulated from the body of incinerator, is provided with a fluid switch, comprising a pair of spaced terminals 125 defining a gap 126 which is closed when the fluid bridges the gap. When the gap is closed, the current flows from the line 104 through the line 105 and the switch gap 126, thence to the motor 106 and ground line 107, thereby starting the time cycle as previously described.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

What is claimed is:

1. Apparatus for the combustion of fecal matter comprising a closet having an opening in the top thereof, a roll of water repellent combustible film in said closet, a horizontal support for said film at the forward end of said closet and subjacent said opening, means at the forward end of said closet adjacent said horizontal support for guiding said film from said support towards the rear of said closet and beneath said opening, the portion of said film beneath and rearward said opening having the sides thereof folded upwardly and converging rearwardly towards each other constituting a trough for the reception of fecal matter, a pair of substantially vertical rollers in said closet rearward said support, spacing means between said rollers near the tops thereof, said spacing means compressively engaging said upwardly folded portion of said film against said rollers and forming it into a narrow U-shaped channel, means selectively actuatable for moving said spacing means rearwardly and rotating said rollers to pull said film beneath said opening and contemporaneously flatten the fecal matter within said U-shaped channel, an incinerator rearward said closet, a conduit constituting a passageway from said closet into said incinerator, said last named means advancing said U-shaped channel of film and the fecal matter therein through said conduit and into said incinerator.

2. Apparatus for the combustion of fecal matter comprising a closet having an opening in the top thereof, a roll of water repellent combustible film in said closet, a horizontal support for said film at the forward end of said closet and subadjacent said opening, means at the forward end of said closet adjacent said horizontal support for guiding said film from said support towards the rear of said closet and beneath said opening, the portion of said film beneath and rearward said opening having the sides thereof folded upwardly and converging rearwardly towards each other constituting a trough for the reception of fecal matter, a pair of substantially vertical rollers in said closet rearward said support, a belt between said rollers adjacent the tops thereof, said belt compressively engaging the upwardly folded portion of said film against said rollers whereby the film is formed into a narrow U-shaped channel between and rearward said rollers, means selectively actuatable for moving the lower run of said belt rearwardly and rotating said rollers to pull said film beneath said opening and contemporaneously flatten the fecal matter contained therein along said narrow U-shaped channel, an incinerator dis-

posed rearward said closet, a conduit constituting a passageway from said closet into said incinerator, said belt advancing said U-shaped channel of film and the fecal matter therein through said conduit and into said incinerator.

3. A dry closet for processing fecal matter for the combustion thereof comprising a closet having an opening in the top thereof, a roll of water repellent combustible film in said closet, a horizontal support for said film at the forward end of said closet and subjacent said opening, means at the forward end of said closet adjacent said horizontal support for guiding said film from said support towards the rear of said closet and beneath said opening, a pair of substantially vertical rollers at the rearward end of said closet, the portion of said film beneath and rearward said opening having the sides thereof folded upwardly and converging towards each other in the direction of said rollers, said portion of said film constituting a trough for the reception of fecal matter, spacing means between said rollers adjacent the tops thereof, said spacing means compressively engaging the upwardly folded portion of said film against said rollers whereby the film is formed into a narrow U-shaped channel between and rearward said rollers, means selectively actuatable for moving said spacing means rearwardly and rotating said rollers to pull said film beneath said opening and contemporaneously flatten the fecal matter contained therein along said narrow U-shaped channel, a container disposed rearward said closet, said rotating means advancing said U-shaped channel of film and the fecal matter therein into said container.

4. Apparatus for the disposal of fecal matter comprising a closet having an opening in the top thereof, a roll of water repellent combustible film in the forward end of said closet, a plate in said closet embodying a substantially horizontal forward edge, said plate being inclined downwardly and rearwardly from the front of said closet, means adjacent the horizontal forward edge of said plate for guiding said film over said plate towards the rear of said closet and beneath said opening, substantially vertical rollers adjacent the rearward end of said plate, the portion of the film forward said rollers constituting a trough with rearwardly convergent sides for the reception of fecal matter, driving means between said rollers compressively engaging the sides of said trough of film between said driving means and said rollers adjacent the tops thereof, said film being formed into a thin U-shaped channel between and rearward said rollers, means selectively actuatable for rotating said rollers and pulling the film and fecal matter thereon between said rollers thereby flattening the fecal matter contained therein along the said U-shaped channel of film, an incinerator adjacent the rear of said closet, a conduit defining a passageway from the opening between said rollers into said incinerator, said pulling and flattening means moving the U-shaped channel of film and fecal matter therein through said conduit and into said incinerator.

5. Apparatus for the disposal of fecal matter comprising a closet, a seat on said closet having an opening therein, a roll of water repellent combustible film disposed horizontally in said closet, a trough in said closet for supporting and guiding said film from said roll of film along a path beneath and facing the opening in said seat, a horizontal forward edge in said trough and rearwardly converging side walls therein for folding said film into an upturned channel for the reception of fecal matter, substantially vertical rollers in said closet adjacent the rearward end of said trough, spacing means between said rollers near the tops thereof, the edges of said upturned channel of film being compressively engaged between said spacing means and said rollers, an incinerator adjacent said closet rearward said rollers, a conduit constituting a passageway from said rollers into said incinerator, means selectively actuatable for effecting the rotation of said rollers whereby said film is pulled beneath

said seat opening and through said trough, thence through and between said rollers to flatten said channel of film and the fecal matter contained therein and contemporaneously pushing said flattened channel and the contained fecal matter through said passageway and into said incinerator.

6. Apparatus for the destruction of fecal matter and urine comprising a closet, a seat thereon having an opening therein, a coil of water repellent paper disposed in 10 said closet, a guideway in the forward end of said closet engaged with a strip of paper, a downwardly inclined plate having upturned side walls defining a trough confronting said seat opening, the upturned side walls of said trough confining said paper strip into channel form having rearwardly converging sides for the reception of fecal matter and urine, substantially vertical rollers at the rearward end of said trough, means between said rollers and near the tops thereof co-acting with said rollers to grip the upturned edges of said channel shaped strip of paper, 20 said means being actuatable at will, an incinerator contiguous the rear of said closet, a conduit from said closet into said incinerator, said gripping means pulling the strip of paper from said coil through said upturned side walls of said trough and between said rollers whereby 25 said paper channel and the fecal matter contained therein is flattened then pushed through said conduit and into said incinerator, a flame generating mechanism in said incinerator, the flame therefrom being directed against said flattened paper channel, the fecal matter and urine therein to effect the destruction thereof.

7. The structure of claim 6 wherein the flame generating mechanism includes means for the cyclic control thereof, and means linked with the actuating means for moving the strip of paper to initiate the operation 30 of the flame generating mechanism.

8. The structure of claim 6 including an exhaust conduit in said incinerator, means in said conduit for directing a substantial portion of the flame into said exhaust conduit to effect the destruction of noxious gases resulting 40 from the combustion of fecal matter as they pass through said exhaust conduit, said means directing the remaining portion of said flame against said flattened strip, fecal matter and urine therein to effect the destruction thereof.

9. Apparatus for the destruction of fecal matter and fluid comprising a closet, a seat thereon having an opening therein, a roll of water repellent combustible paper supported horizontally in said closet, a plate in one end 50 of said closet to support and guide a strip of paper from said roll in the form of a trough under said seat opening for the reception of fecal matter and fluids, spaced vertical rollers adjacent the rearward end of said plate, means engaged between said rollers selectively actuatable for rotating said rollers and engageable with the strip of paper for pulling the strip of paper from said roller and over said plate and through said rollers, the portion of the strip entering said rollers defining a narrow U-shaped paper channel, said rollers flattening the fecal matter therein as it is moved therethrough, an incinerator adjacent the rear of said closet, a conduit defining a passageway from the opening between said rollers into 60 said incinerator for the passage of said U-shaped paper channel into the incinerator as it emerges from said rollers, an evaporating pan in said incinerator subjacent the end of said passageway for the reception of fluid drained from said U-shaped paper channel, a flame generating mechanism in said incinerator arranged to direct a flame over said evaporating pan and against said paper U-shaped channel and the fecal matter contained therein to effect evaporation of the fluid and the destruction 65 of said U-shaped paper channel and fecal matter therein, means for the cyclic control of said flame generating mechanism, and means connected to said roller actuating means for initiating said cyclic flame control means.

10. The structure of claim 9 wherein the means associated with said flame generating mechanism for the

cyclic control thereof includes means in said evaporating pan to initiate the operation of said cycle when the level of liquid in the pan reaches a predetermined height.

11. A dry closet for the combustion of fecal matter comprising a bowl, a seat thereon having an opening therein, a roll of paper disposed horizontally in said bowl, a rearwardly inclined plate in said bowl, the forward edge thereof being horizontal and the rearward sides thereof being folded upwardly defining a trough for supporting and guiding the paper from said roll in a path under and facing said seat opening, the upturned sides in the rearward portion of said plate folding the paper into a paper channel for the reception of fecal matter, a pair of spaced substantially vertically disposed rollers in said bowl adjacent the end of the upturned sides of said plate, a horizontal shaft in said bowl adjacent said rollers, a pawl keyed thereon, a ratchet wheel engaged therewith, a pulley loosely mounted on said shaft and connected to said ratchet wheel for unidirectional rotation thereof, a second horizontal shaft in said bowl, a second pulley thereon disposed in aligned relation with the first named pulley, a belt carried by said pulleys engaged between said rollers adjacent the tops thereof, the edges of said paper channel being compressively engaged between said belt and said rollers, mechanism actuatable at will for rocking the first-named shaft to engage said pawl with said ratchet wheel, said first-named pulley effecting the translation of the lower run of said belt rearwardly thereby rotating said rollers and pulling the paper from said roll and through said trough, said rollers flattening said paper channel and the contained fecal matter and discharging the flattened paper channel rearwardly, means for tightening said belt, and an incinerator at the rear of said bowl having a passageway therein aligned with the paper channel as it emerges from the rollers, said incinerator burning said paper channel and the contained fecal matter when fed into the incinerator.

12. Apparatus for the combustion of fecal matter comprising a closet, a seat thereon having an opening therein, a roll of water repellent paper in said closet, mechanism to support and guide the paper from said roll under said seat opening, supporting and guiding mechanism for folding the paper beneath said seat opening into a channel having upturned rearwardly converging sides for the reception of fecal matter, a pair of spaced substantially vertical rollers in said closet for flattening said channel together with fecal matter contained therein, mechanism co-acting with said rollers selectively actuatable for drawing said paper channel beneath said seat opening and between said rollers, an incinerator rearward said closet, a frame defining a passageway into said incinerator and in substantial alignment with the opening between said rollers, a closure plate in said frame movable across said passageway, flame quenching facing on said plate and on the opposed side of said frame to inhibit ignition of said paper channel outside of said incinerator and for sealing said passageway when in closed position, means connected with the mechanism for rotating said rollers to move and hold said closure plate into closed position when the rollers are at rest and to move said closure plate into its open position in said passageway for the movement of said flattened paper channel into said incinerator when the rollers are actuated, and a burner in said incinerator for the combustion of said flattened channel and fecal matter carried thereby.

UNITED STATES PATENT OFFICE
CERTIFICATE OF CORRECTION

Patent No. 2,835,214

May 20, 1958

George O. Harm

It is hereby certified that error appears in the printed specification of the above numbered patent requiring correction and that the said Letters Patent should read as corrected below.

Column 3, line 45, for "attained, the" read -- attained, then --; column 5, line 44, for "solenoid 17" read -- solenoid 117 --.

Signed and sealed this 8th day of July 1958.
